UNITED STATES PATENT OFFICE.

FELIX EBERHART, OF NEW YORK, N. Y., ASSIGNOR TO AMERICAN CAN COMPANY, OF NEW YORK, N. Y., A CORPORATION OF NEW JERSEY.

SHEET-METAL POCKET TOBACCO-BOX.

No. 918,519.

Specification of Letters Patent.

Patented April 20, 1909.

Application filed October 24, 1908. Serial No. 459,827.

To all whom it may concern:

Be it known that I, FELIX EBERHART, a citizen of the United States, residing in New York, in the county of New York and State of New York, have invented a new and useful Improvement in Sheet-Metal Pocket Tobacco-Boxes, of which the following is a specification.

My invention relates to improvements in the construction of sheet metal boxes or receptacles for tobacco or other articles.

Pocket tobacco boxes of the kind to which my invention particularly relates, have heretofore ordinarily been provided with a pouring opening in the flat top head or cover of the box closed by a flat reciprocating slide fitting in suitable guides on the top head; and frequently either the flat slide or the flat head on which it is mounted becomes so bent out of shape by the pressure of the thumb thereagainst in opening and closing the slide as to render the box difficult or impossible to open, a difficulty that is aggravated as there is no means of flattening or straightening out the bends.

The object of my invention is to provide an improved construction of pocket box by which such difficulties may be obviated or overcome, and in which at the same time the other parts of the box will be adapted for cooperative use with an ordinary slip cover, if desired, instead of with the customary double seamed or permanently secured top head so that the box may be refilled with tobacco by the customer or user.

My invention consists in a sheet metal pocket box having a wide thin body with the customary substantially flat or slightly curved back and front walls and trough shaped edge walls. (that is to say, sharply curved or angular edge walls,) one of which is provided near one end with a pouring opening, and a trough shaped, (that is to say, sharply curved or angular) reciprocating closure slide for closing the pouring opening and suitable interengaging guides on the body and closure slide, the trough shape of the closure slide and of the body wall against which it fits serving to so stiffen and strengthen these parts that no ordinary pressure of the thumb or fingers in opening or closing the slide can bend or distort either out of shape so as to interfere with their proper cooperative operation.

The invention further consists in the novel

construction of parts and devices and in the novel combinations of parts and devices herein shown and described and more particularly specified in the claims.

In the accompanying drawing forming a part of this specification, Figure 1 is a perspective view of a sheet metal pocket tobacco box embodying my invention. Fig. 2 is a detail side elevation showing the closure slide partially open and the slip cover removed. Fig. 3 is a vertical longitudinal section on line 3-3 of Fig. 1. Fig. 4 is a cross section on line 4-4 of Fig. 3. Fig. 5 is a cross section on line 5-5 of Fig. 3, and Fig. 6 is a cross sectional view illustrating a modification in which the trough shaped edge wall instead of being sharply curved, is made angular.

In the drawing, 1 represents a sheet metal pocket box or receptacle having substantially flat or slightly curved back and front walls 2, 3, and trough shaped edge walls 4, 5, preferably sharply curved and merging into the curvature of the back and front walls so as to give the body of the box a general oval or thin wide shape suitable for carrying in the pocket. The side seam 6 is preferably an internally folded one and located at one of the trough shaped edge walls. The bottom head 7 of the box or vessel is preferably furnished with a countersunk wall 8 which fits inside the lower end of the body and this bottom head is preferably secured to the body by a double or folded seam 9. The cover or top head 10 may be either permanently seamed or secured to the body like the bottom head if desired, but it is preferably of a tight fitting slip cover construction; that is to say, provided with a slip cover flange 11 snugly embracing the upper or mouth end 12 of the body. This gives additional convenience in filling the box and also enables it to be refilled by the customer or user.

The body of the box is provided at one of its trough shaped edge walls near the upper end thereof with a pouring opening 13 which is opened and closed by an inside fitting reciprocating trough shaped slide 14 conforming in shape to the trough shaped edge wall of the box body. The trough shaped closure slide 14 and the trough shaped edge wall of the body to which such slide is applied, are provided with interengaging guides to slidably connect said parts together. These

interengaging guides 15, 16 may be of any suitable kind or construction. Same preferably consists of a longitudinally extending slot or groove in the body member and a rivet or projection on the slide member. The rivet or projection 16 on the slide member is preferably furnished with a head 17 which overlaps or engages the edges 18 of the guide groove 15, and said edges are preferably furnished with a locking or holding device 19, preferably consisting of a slight hump so as to properly lock or hold the closure slide in its uppermost or closed position. The pouring opening 13 in the trough shaped edge wall preferably does not extend to the upper end of the edge wall, an integral bridge wall 20 being left above the opening so that the mouth end of the body which engages the slip cover flange may be continuous and thus enable the slip cover flange to have a tight and secure frictional engagement with the body.

In the modification illustrated in Fig. 6, the trough shaped edge wall is made angular instead of sharply curved and the closure slide is correspondingly shaped. Whether the trough shaped closure slide is made angular or sharply curved, the wing or side portions 21, 21 thereof by the spring or resilient action of the sheet metal produce a snug fit between the closure slide and the body and thus effects a tight closure, while at the same time giving the necessary strength and stiffness to prevent any pressure upon the slide from bending or distorting it out of shape, and the trough shape of the edge wall of the body, whether it is curved or angular, also gives it such strength and stiffness as to prevent its being bent out of shape. My improved construction of pocket tobacco box and closure slide there-

fore is thus at one and the same time easily operated, strong and durable, and effects a tight closure.

My improved box is preferably made of sheet metal, but it may be made of paper in whole or in part.

I claim:

1. A sheet metal pocket box comprising a wide thin body with substantially flat or slightly curved back and front walls and trough shaped edge walls, one of which edge walls is furnished with a pouring opening, an inside fitting reciprocating trough shaped slide for opening and closing said opening in the body, the body having a guide groove furnished with a locking hump and the slide having a guide rivet or device furnished with a head engaging the locking hump, substantially as specified.

2. A sheet metal box comprising a cover and a body having a trough-shaped wall provided with a pouring opening, a reciprocating trough-shaped closure slide independent of the cover, and inter-engaging guides on said trough-shaped end wall and closure slide, substantially as specified.

3. In a sheet metal box, the combination with a body having a curved wall provided with a pouring opening, of a reciprocating curved slide for closing said opening, a guide groove or slot in the curved wall of the body having the edge thereof furnished with a locking hump and a guide rivet on the slide having the edge adapted to engage said hump on the edge and lock the slide in its closed position, substantially as specified.

FELIX EBERHART.
